2,827,926AUTOMATIC BALING MACHINE AND A
BANDING MECHANISM THEREFOR

Robert E. Seltzer, Bellevue, Ohio, assignor to The American Baler Company, Bellevue, Ohio, a corporation of Ohio

Original application April 15, 1952, Serial No. 282,429, now Patent No. 2,768,574, dated October 30, 1956. Divided and this application June 9, 1953, Serial No. 360,403

11 Claims. (Cl. 140—111)

This application relates to automatic baling machines, particularly to a banding mechanism therefor, and is a division of my co-pending application, Serial No. 282,429, filed April 15, 1952, now Patent No. 2,768,574.

In the co-pending application referred to above I show a full automatic baling machine particularly adapted for industrial use in the baling of wastes and the like, and in which the material to be baled is delivered to a compression chamber from a chute or hopper and is pushed from the compression chamber into a baling chamber where it is pressed into the form of a bale during its travel therethrough, and with an automatic banding mechanism being provided which automatically passes wires about the bales when they reach a predetermined size and twists the ends of the wires together.

The present application deals in particular with the novel mechanism associated with such a baling machine, by means of which the ends of the wires are twisted together and cut off during the automatic and continuing cycling of the baling machine.

A primary object of the present invention is the provision of a novel arrangement for effecting the cutting off and the twisting together of a banding wire for a bale such as is produced in the type of baling machine referred to.

Another object of this invention is the provision of a twisting and cutoff unit for banding wire of a bale which prevents any raw edges of the cutoff wire from protruding from the bale.

A still further object is the provision of a twister head and cutoff unit for twisting together and cutting off the banding wire of a bale which can be associated with like units to perform twisting and cutoff operations on a plurality of wires at one time.

Another particular object of the present invention is the provision of a twister head and cutoff unit for twisting together and cutting off the banding wire of a bale in which the wire is tightly twisted together, but is prevented from sticking on the twister head.

Still another particular object is the provision of a wire cutoff and twister head of the nature referred to which is rapid in operation, thus requiring a small amount of time for accomplishing the cutoff and twisting operation whereby the cycling of the baler is interrupted to only a small degree.

A still further object is the provision of a cutoff and twister unit of the nature referred to which will be relatively simple to construct and which is basically strong thereby requiring the minimum amount of service and being adapted for remaining in operative condition for a long period of time.

These and other objects and advantages of this invention will become more apparent upon reference to the following specification taken in connection with the accompanying drawings, in which:

Figure 1 is a side elevational view of an automatic baling machine embodying a wire twisting and cutoff unit according to this invention;

2

Figure 2 is a vertical section indicated by cutting plane 2—2 on Figure 1 and showing the twister and cutoff unit in vertical section;

Figure 3 is a bottom plan view of the unit looking up from beneath as indicated by the arrow 3 on Figure 1;

Figure 4 is a plan view looking down on top of the twister and cutoff unit as it is seen in Figure 2, but with the top cover thereof removed;

Figure 5 is a sectional view indicated by line 5—5 on Figure 4 showing in some detail the construction and arrangement of the parts of one section of the twister and cutoff unit;

Figure 6 is a sectional view indicated by line 6—6 on Figure 4 showing a pin and slot arrangement for guiding one of the elements of the twister portion of the unit, first the reciprocatory movement and then the rotary movement;

Figure 7 is a section indicated by line 7—7 on Figure 6 showing another portion of the mechanism of Figure 6;

Figure 8 is a sectional view indicated by line 8—8 on Figure 4 showing still another portion of the said mechanism;

Figure 9 is a sectional view indicated by line 9—9 on Figure 4 illustrating the rotary cutoff mechanism forming a part of the unit;

Figure 10 is a view looking in at the side edge of the rotary cutoff unit illustrated in Figure 9;

Figure 11 is a sectional view indicated by line 11—11 on Figure 4 showing the actuating cam that cooperates with the rotary cutoff head;

Figure 12 is a sectional view taken through the rotary cutoff head as indicated by line 12—12 on Figure 9 showing the cutoff head in position relative to the actuating cam of Figure 11 for gripping a wire that is to be cut off;

Figure 13 is a sectional view like Figure 12 but shows the cutoff head in position relative to the cam for releasing the wire;

Figure 14 is a side view showing the construction of the slotted outer end of the twister rod of the unit;

Figure 15 is a plan view of the slotted end of the twister rod;

Figure 16 is an end view looking in at the slotted end of the twister rod;

Figure 17 is a plan sectional view somewhat diagrammatic and generally indicated by line 17—17 on Figure 1 showing the position of the parts of the machine at the initiation of a baling cycle with the wire thrust across at the back end of the bale;

Figure 18 is a fragmentary view similar to Figure 17 but showing the twister and cutoff unit advanced to receive the banding wire in the slot at the end of the twister rod;

Figure 19 is a fragmentary view showing the position occupied by the rotary cutoff head relative to the banding wire when the twister and cutoff unit is in its Figure 18 position;

Figure 20 is a fragmentary view showing how the banding wire is received in the slotted end when the twister and cutoff unit is in its Figure 18 position;

Figure 21 is a fragmentary view similar to Figures 17 and 18, but showing the banding wire twisted on the end of the twister rod;

Figure 22 is an enlarged view showing the appearance of the wire after it has been twisted by the twister rod;

Figure 23 is a fragmentary view showing the rotary cutoff head in the position it occupies just as the wire is cut off;

Figure 24 is a fragmentary view similar to Figures 17, 18 and 21, but showing the mechanism at the time the wire is tucked into the corner of the bale; and

Figure 25 is an enlarged fragmentary view showing more in detail the tucking in of the ends of the cutoff banding wire.

The general arrangement of a baling machine adapted for having incorporated therewith a wire twisting and cutoff arrangement according to the present invention is illustrated in Figure 1, wherein a hopper or chute H supplies material to be baled to a compression chamber C whence it is pressed by the ram or baling head R into a baling chamber B wherein it takes the form of a bale that is to be banded by wires that will be twisted and cut off by the twister and cutoff unit according to this invention and which is indicated at T in Figure 1.

The ram or baling head R is adapted for being driven by a hydraulic motor M supplied by fluid under pressure by the power unit P.

The bales being formed are pushed through the baling chamber beneath a measuring mechanism N which includes a wheel that bears on the bales being made so as to be turned thereby and which serves automatically to initiate a banding operation when the bale reaches a predetermined length, and which banding operation consists of thrusting banding wires across the back of the bale and twisting them together at one corner of the bale, cutting the wires off, and tucking the raw ends of the wires into the corner of the bale.

In the arrangement illustrated the banding wires for the bales are indicated at W, and it will be seen that there are three in number. A greater or lesser number of banding wires could be provided depending upon the individual circumstances, such as the type of waste for the material being baled, the size of the bales, and various other factors.

The unit indicated at T in Figure 1, and which is the twisting and cutoff unit, comprises a frame 10 that is movably supported on the adjacent side wall of compression chamber C as by the track means 12 on the said chamber and the roller means 14 carried by the unit T. This arrangement is provided so the unit T can be moved longitudinally of the compression chamber into operative position to engage the banding wires of the bale at the back corner thereof for a twisting and cutting off cycle, and can then be retracted from the said position during continued operation of the baling machine while another bale is being built up. In Figure 1, the point where the wires are thrust across at the back of the bale to be engaged by the twister unit and twisted thereby, is indicated by the heavy dot-dash line 16.

By way of a brief description of an operative cycle reference may be had to Figures 17, 18, 21 and 24.

In Figure 17, which is a plan section through a bale at the level of one of the banding wires, it will be seen that a needle 18 has been thrust across the back of the bale 20 carrying the banding wire W across the back of the bale in the form of a loop, the one end of the wire W being fastened to a portion of the twister unit and the other end thereof extending to the reel of wire 22 positioned on the opposite side of the baling machine from the twister unit.

In Figure 18 the twister unit has advanced longitudinally of the baling machine and has engaged the wire W at the point where it crosses at the back corner of the bale.

In Figure 21 the twister unit has operated to sever the wire and to grip the end thereof that leads directly to the reel 22 while simultaneously the two ends of the banding wire passing around the bale have been twisted together.

In Figure 24 the twister unit is illustrated in the operation of tucking in to the corner of the bale the cut off ends so that no wire ends project from the bale. Thereafter the twister unit will retract and then the needle will retract and operation of the baling machine will be resumed.

With reference now to the particular construction of the twisting and cutoff unit, reference may first be had to Figures 2 through 8.

In Figure 2, which is a vertical section taken through the twister unit T, as indicated on Figure 1, will be observed that frame 10 of the unit comprises a plurality of superimposed sub-frames 30 which may be interconnected as by the corner clips 32. This arrangement permits the stacking of the individual twister units to provide for as many thereof as may be needed in any particular circumstance.

Each sub-unit of the twister unit comprises, in addition to the sub-frame unit 30, a twister rod 34 having slot 36 in its outer end, which slot is adapted for receiving the crossed ends of the banding wire with the rod being rotatable for twisting the said ends together.

Reciprocably and rotatably mounted about each twister rod 34 is a tucker sleeve 38 having an end portion 40 with a notch 42. The tucker sleeve is for the purpose of stripping the wire from the twister rod and for tucking the raw ends thereof into the corner of the bale.

The actuating mechanism for rotating the twister rod and reciprocating and rotating the tucker sleeve will be seen in Figures 4 through 8 taken in connection with Figure 2.

Referring particularly to Figure 5, it will be noted that twister rod 34 is rotatably supported by bearings 44 and 46 in tucker sleeve 38, and also in a bearing 48 that is mounted in a sleeve 50 that is rigid with a plate 52 that extends beyond and is rigidly connected with the side walls of the pertaining sub-frame unit 30, as will best be seen in Figure 4.

Rod 34 has keyed thereto a spur gear 54 that meshes with an idler gear 56 (Figures 2 and 4) that is supported by plate 52, while an idler gear 57, also supported by plate 52, meshes with idler gear 56 and with a gear 58 pinned to a shaft 60. Shaft 60 is journaled in a bearing 62 carried by sleeve 64 mounted in wall 52 and also by a bearing 66 mounted in sleeve 68 that is rigid with the front wall of the pertaining sub-frame 30.

Shaft 60, at its rear end, carries a bevel gear 70 which is engaged and driven by another bevel gear as will be explained more in detail hereinafter.

Rotatably mounted about tucker sleeve 38 is a cutoff and gripper head 72 which is supported on the tucker sleeve 38 by the bearings 74, and is also supported by the bearings 76 within a sleeve 78 rigid with the front wall of the pertaining sub-frame 30.

Sleeve 78 also carries a stationary cam 80 that operates with the cutoff and gripper head in a manner to be described hereinafter.

Within sub-frame 30 the cutoff and gripper head 72 carries a gear 82 which meshes with a gear 84 pinned to shaft 60.

At this point it will be evident that rotation of bevel gear 70 will cause rotation of shaft 60 which, in turn, will drive through gears 58, 57, 56 and 54 into twister rod 34 to rotate the latter, and through gears 84 and 82 into the cutoff and gripper head 72 to also rotate this element. It also will be evident that the twister rod will rotate at greater speed than the cutoff and gripper head and in an opposite direction. Specifically, the twister rod rotates an even multiple of the number of revolutions of the gripper head so that for each 180° of revolution of the gripper head, the twister rod returns to its starting position.

Turning now to the tucker sleeve 38, this element between gears 54 and 82 is formed as at 86 with a worm thread which is in mesh with a helical gear 88 fixed to the vertically extending shaft 90.

The tucker sleeve 38 is adapted for being driven in reciprocation and rotation by gear 88, and this is accomplished in an arrangement best seen in Figures 4 through 8.

In Figures 4 and 6 it will be observed that mounted

on one of the side walls of the pertaining sub-frame 30 is a block 91 which extends inwardly to the region of the threaded portion of tucker sleeve 38. This block 91 is formed with an axial slot 92 extending lengthwise of the axis of the tucker sleeve and at one end is intersected by a circumferential slot 94. Secured to the tucker sleeve 38, adjacent the rear end of the threaded portion thereof, is a rod 96 having a head 98 thereon fitting relatively closely within slot 92. It will be apparent that upon rotation of helical gear 88 the tucker sleeve 38 will first be driven in reciprocation because of the engagement of head 98 with rod 96 and with slot 92, and when the said head reaches the front end of slot 92 the tucker sleeve will commence to rotate and the head 98 will then travel in circumferential slot 94. Upon reversing the direction of rotation of helical gear 88 the opposite series of events will occur and the tucker sleeve will first rotate back to its original angular position and will then reciprocate back to its original axial position.

It has been mentioned previously that the twister unit T, as illustrated in Figure 1, consists of a plurality of stacked sub-units, and reference to Figure 2 will illustrate how the sub-units are drivingly interconnected after being stacked. The shafts 90 of the several sub-units which carry the helical gears 88 are drivingly connected by the couplings 100, and the lowermost one of shafts 90 is coupled with a shaft 102 journaled in and extending down through the bottom wall of the lowest one of the said sub-units.

It has also previously been mentioned that the bevel gears 70 are drivingly engaged by suitable gears, and this arrangement is also illustrated in Figure 2 wherein it will be seen that each of the bevel gears 70 is engaged by a crown gear 104, with each crown gear being carried by a shaft 106 journaled on the pertaining sub-unit by a bearing 108. The several shafts 106 are detachably drivingly interconnected by the couplings 110 and the lowermost shaft 106 is coupled by the coupling 110 with shaft 112 extending through and journaled in the bottom wall of the lowermost sub-unit.

The actuating means for driving the shafts 90 and 106 will be seen in Figures 2 and 3. In these views there will be seen the hydraulic cylinder 114 in which is reciprocably mounted a double-acting ram including a plunger 116 connected at 118 to a plate 120 which is rotatable on the lower end of shaft 112. Plate 120 has pivoted thereto at 122 a pawl 124 adapted for engagement with notches 126 in the periphery of ratchet plate 128 that is secured to the lower end of shaft 112. The pawl 124 is spring urged against the periphery of ratchet plate 128 by spring 130 and the notches 126 are so shaped that when the plate 120 rotates in a clockwise direction, as it is viewed in Figure 3, the pawl will drive the ratchet plate 128, but when the plate 120 is driven in the opposite direction the pawl will cam out of the notch with which it is engaged and return idly.

For reasons which will become apparent hereinafter, after ratchet plate 128 has been actuated by a clockwise movement of plate 120, it is desired to obtain a small amount of reverse movement of the said ratchet plate. For this purpose there is mounted adjacent the periphery of the ratchet plate a member 132 having a nose 134 which will engage the back surface of pawl 124 before it has completed its driving movement during clockwise travel of plate 120. Then, when plate 120 is reversed to move in a counterclockwise direction, nose 134 of member 132 will retain pawl 124 engaged with ratchet plate 128 until the said pawl passes from beneath nose 134, whereupon the pawl will then cam out of the notch with which it is engaged and return idly to its Figure 3 position.

The gearing between shaft 106 and the gripper heads is such that the gripper heads are turned slightly more

than 180° during the said clockwise movement of plate 120, and the shaft and arc then backed up slightly when the plate 120 makes its slight counterclockwise movement as described.

The integration of the twisting and tucking cycle requires that the twister rod rotate in advance of the operation of the tucker sleeve, and the delay in the operation of the tucker sleeve is obtained by providing plate 120 with a slot 140 in which there is a pin 142 connected to a bar 144 that carries a rack or reciprocable member 146 meshing with a gear 148 on the lower end of shaft 102. It will be apparent that upon rotation of plate 120 in a clockwise direction from its Figure 3 position the said plate will rotate through a substantial angle before bar 144 will commence to move relative to gear 148, and that, accordingly, the twister rod 34 will have rotated a predetermined amount before the tucker sleeve commences to operate.

Turning now to the cutoff and gripper head 72, this portion of the mechanism will best be seen in Figures 2, 4, 5 and 9 through 13.

The front face of cutoff and gripper head 72 is bevelled at the periphery and mounted at diagrammatically opposite points on the cutoff and gripper head on the said bevel or the gripper blocks 150, each of which has a projecting nose 152, as can be seen in Figures 9 and 11 through 13. Each said nose portion has a recess 154 therein, and reciprocably mounted in the cutoff and gripper head directly opposite the said recess is a pin 156 biased away from the said recess by spring 158. The ends of pins 156 opposite the recess 154 bear on the stationary cam 80, which consists of a lower portion 160 and a raised portion 162. When the pins are riding along the lower portion 160 of cam 80, the pins are spaced a substantial distance from their pertaining recesses, but when the pins are riding on the high part of raised portion 162 of the cam they are urged toward their pertaining recesses so as to crimp and grip a wire therein.

In Figure 13 a pin is shown riding on the lower portion 160 of cam 80 with the wire W crimped into the recess but not held therein by the pin 156, whereas in Figure 12 the said pin is shown riding on the high part 162 of the cam 80, and in this position the wire W is gripped by said pin.

Carried on the back surface of the cutoff head adjacent each of the blocks 150 is a shearing blade 164, each of which is adapted for cooperation with a stationary shearing blade 166 (Figure 2) so that as the cutoff and gripper head rotates a wire that is extending through the notched shearing blade 164 adjacent the stationary shearing blade will be sheared off by the said shearing blade.

The notched end of the twister rod 34 is advantageously formed, as is illustrated in some detail in Figures 14, 15 and 16, wherein it will be seen that the twister rod has a V shaped transverse recess 170 therein, and is then drilled axially as illustrated at 172. The end of the rod is then milled lengthwise on opposite sides of the drilled hole with parallel slots that are also on opposite sides of the transverse center line of the rod as is illustrated at 174. At the bottom of this last-mentioned milled slot a V shaped configuration is formed inwardly of the axis of the said rod and inclined angularly about 45° toward the outer end thereof. These drilled portions are indicated at 176. The arrangement is such that when a pair of crossed wires is received in the notched end of the twister rod and the twister rod then rotated for twisting the wires together, the enlarged central part of the notched end of the rod receives the twisted together part of the wires, while the undercut portions at 176 tend to receive and retain the projecting ends of the wires. The wires thus have little tendency to slip out of the notch at the end of the twisting rod when the twisting has been commenced.

7
Operation

To describe the operation of the device of this invention, let it be assumed that the machine is in the condition illustrated diagrammatically in Figure 17, wherein the wire W is gripped by the cutoff and gripper head 72 and then passes over the notched end of the twister rod 34 down along the side of the bale 20 across the front end thereof and then back along the opposite side of the bale. The wire, immediately prior to the machine coming to its Figure 17 position, was thrust across the back of the bale by the needle 18 which was actuated in response to the measuring disk or wheel within the measuring mechanism N (Fig. 1) having determined that the bale was of the proper length and bringing about the halting of the baling head R in its advanced position and the actuation of the needle to its Figure 17 position.

After needle 18 has been thrust across to its Figure 17 position, the twister unit advances longitudinally of the baling machine so that the notched end of the twister rod 34 engages that reach of wire W which is passing across the back of the bale as indicated in Figure 18. Simultaneously, the cutoff and gripper head 72 has moved into position where the block 150 thereon, opposite the one which is visible in Figures 17 and 18, is positioned immediately above the reach of the wire W that goes across the back of the bale and to the reel 22. This is illustrated in Figure 19, and it will be apparent that when the cutoff and gripper head rotates the wire will be picked up by the block 150 and the cutoff blade 164.

The relative positions occupied by the parts of the wire that are to be twisted together within notch 36 is illustrated in Figure 20.

With the twister unit now in position the motor, consisting of cylinder 114 and the double-acting ram therein to which rod 116 is connected, is energized to rotate plate 120 in a clockwise direction as it is viewed in Figure 3. This movement of plate 20 will cause rotation of the cutoff and twister heads in the direction indicated by the arrows thereon in the several views whereby the reach of wire W leading to reel 22 will be picked up and gripped thereby and sheared off by shearing blade 166.

Simultaneously, the twister rod 34 will be driven in rotation in the opposite direction to bring about twisting together of the ends of the wire W that are deposited in the notch 36, as illustrated in Figures 18 and 20. Shortly after the twisting of the wires commences the end thereof gripped by the gripper head in Figures 17 and 18 will be released therefrom, but, inasmuch as the wire is already twisted this will not cause any loosening of the band passing around the bale.

The appearance of the wire when it is substantially completely twisted is illustrated in Figures 21 and 22.

In Figure 22, in particular, it will be noted that the cutoff ends of the wire that has been twisted are extended through the notch 42 in the nose 40 of the tucker sleeve 38. This fact is availed of for tucking the raw ends of the wire into the corner of the bale by thrusting the tucker sleeve forwardly and then causing it to rotate. This comes about because toward the end of the twisting operation, the bar 144 will commence to move with plate 120 and drive shaft 102 and shafts 90 to cause first reciprocation and then rotation of the several tucker sleeves 38 in the manner described which will bring the said tucker sleeves to the position illustrated in Figure 24.

As will be seen in Figure 25, the tucker sleeve at this time has tucked the raw ends of the wire into the corner of the bale. The total amount of rotation of the gripper heads is slightly greater than 180° and that of the twister rods some even multiple thereof.

At this time the energization of the hydraulic actuating

motor for the twister unit is reversed, which will cause a small amount of reverse rotation of the shaft 106 due to the action of nose 134 of member 132 in retaining pawl 124 in engagement with ratchet plate 128 for a short time. This causes the gripper heads to turn back to a point just 180° from their starting points. This will also provide for a small amount of reverse movement of the twister rods which will insure that they will all release from the wires with which they are associated so that after the actuating motor for the twister unit has fully retracted, thus returning the tucker sleeves to their original positions, the entire twister unit can be retracted to its Figure 1 position along the side of the baler and all of the twister rods will be released from their pertaining twisted wires.

At this time the wire W extends from a gripped position on the cutoff and gripper head across the face of baling head R to reel 22, so that, after the baling head is again set into operation, the bale built up thereby will push the wire ahead of it so that the wire will once again be engaged by the notch at the end of the twister rod and pass along one side of the bale, then across the front thereof, and then along the other side thereof and across the end of the pertaining needle and back to reel 22.

It will be understood that the initiation of the banding cycle, including the operation of the twister and cutoff unit, could be initiated automatically in response to the building up of a bale of a predetermined size in the machine. The particular mechanism by which this automaticity of operation is obtained is more fully disclosed in my co-pending application, Serial No. 282,429, filed April 15, 1952, now Patent No. 2,768,574 of which the present application is a division.

It will be understood that this invention is susceptible to modification in order to adapt it to different usages and conditions, and accordingly, it is desired to comprehend such modifications within this invention as may fall within the scope of the appended claims.

I claim:

1. In a twisting and tucking unit of the nature described; a twister rod having a slot at one end to receive crossed wires to be twisted, a tucker sleeve surrounding said rod and having a nose portion with a lateral notch positioned so that rotation of said rod to twist the crossed wires together will cause the ends of the wires to be engaged by the notch in the end of the sleeve, means for rotating said rod in one direction, means for reciprocating said sleeve on said rod and rotating the said sleeve on the rod to tuck the ends of the wires inside the twisted together portion thereof, means for retracting said sleeve, and means for turning said rod a small amount in the opposite direction to loosen the twisted wires therefrom.

2. In a twisting and tucking arrangement of the nature described; a rotatable twister rod having a slotted end to receive crossed wires to be twisted, a tucker sleeve rotatably and reciprocably mounted about said rod and comprising a nose portion with a lateral notch to engage the end portions of the wires being twisted by said rod, means for rotating said rod in one direction to effect the twisting together of the wires in the slotted end thereof, and said means also being operable for reciprocating said sleeve on said rod and for rotating said sleeve in a direction opposite to the direction of rotation of the said rod for tucking the said end portion of the wires inside the twisted together portion thereof, said means also being operable for retracting said sleeve to its initial position while simultaneously turning said rod to a small angle in the said opposite direction to loosen the wires therefrom.

3. In a twisting and tucking unit of the nature described; a rotatable twister rod having a slotted end to receive crossed wires to be twisted, a tucker sleeve rotatable and reciprocable on said rod having a nose portion

with a lateral notch to receive the projected end portions of the wires being twisted by said rod and operable when reciprocated and rotated on said rod to tuck the said projected ends of said wires under the twisted together portions of said wires, a first shaft connected with said rod rotatable in one direction for rotating said rod in one direction, a second shaft connected with said sleeve rotatable in one direction for first reciprocating said sleeve on said rod and for then rotating said sleeve on said rod, and motor means connected with said shafts operable for driving first only said first shaft in its said one direction, and then for driving said shafts together in said one direction, and then for causing a small amount of reverse rotation of said first shaft and returning said second shaft to its original position.

4. In a twister unit of the nature described; a twister rod having a slotted end to receive crossed wires to be twisted, a tucker sleeve rotatably and reciprocably mounted about said rod having a nose portion with a lateral notch to receive the projecting end portions of the wires being twisted, a gripper head rotatably mounted about said sleeve and rod and having means for gripping a wire, stationary cam means for actuating said gripping means during rotation of said gripper head, means for simultaneously rotating said rod and said gripper head, means operable after a predetermined amount of rotary movement of said gripper head and rod for first reciprocating and then rotating said tucker sleeve on said rod, and means for retracting said tucker sleeve to its original position.

5. In a twister unit of the nature described; a twister rod having a slotted end to receive crossed wires to be twisted, a tucker sleeve rotatably and reciprocably mounted about said rod having a nose portion with a lateral notch to receive the projecting end portions of the wires being twisted, a gripper head rotatably mounted about said sleeve and rod and having means for gripping a wire, stationary cam means for actuating said gripping means during rotation of said gripper head, means for simultaneously rotating said rod and said gripper head, means operable after a predetermined amount of rotary movement of said gripper head and rod for first reciprocating and then rotating said tucker sleeve on said rod, and means for retracting said tucker sleeve to its original position, said means for rotating said gripper head and twister rod being operable to rotate said gripper head through an angle of slightly more than 180° while rotating said rod through an angle that is a multiple of the angle through which the gripper head is moved, and said means also being operable for retracting said gripper head the amount of rotation that has been rotated in excess of 180°.

6. In a twister unit of the nature described; a twister rod having an axially slotted end to receive crossed wires to be twisted, a gripper and cutoff head rotatably mounted about said rod, said cutoff head having diametrically opposite grippers thereon adapted for gripping a wire to be twisted together with another wire and having a rest position where one of the gripper means is in actuated position and the other thereof is in idle position, means gearing said gripper head and rod together so that the rod will rotate a multiple of half-revolutions while the gripper head rotates one half-revolution, means for driving said gripper head and rod in rotation so the gripper head makes slightly more than one half-revolution during a twisting cycle, and means for retracting said gripper head together with said rod an amount equal to the overtravel of said gripper head beyond 180°.

7. In a twister unit of the nature described; a twister rod having an axially slotted end to receive crossed wires to be twisted, a gripper and cutoff head rotatably mounted about said rod, said cutoff head having diametrically opposite grippers thereon adapted for gripping a wire to be twisted together with another wire and having a rest position where one of the gripper means is in actuated posi-

tion and the other thereof is in idle position, means gearing said gripper head and rod together so that the rod will rotate a multiple of half-revolutions while the gripper head rotates one half-revolution, means for driving said gripper head and rod in rotation so the gripper head makes slightly more than one half-revolution during a twisting cycle, and means for retracting said gripper head together with said rod an amount equal to the overtravel of said gripper head beyond 180°, said driving means comprising a ratchet plate, a driving member, a pawl on the driving member engageable with the notches on said ratchet plate operable for positively driving said ratchet plate in one direction, and stationary cam means engageable with said pawl as it approaches the end of its movement in the driving direction thereof for retaining said pawl in engagement with the pertaining notch of the ratchet plate so that upon reverse movement of said drive member the ratchet plate will be driven in the reverse direction until the said pawl is released from said cam member.

20 8. In a twister unit of the nature described; a frame, a twister rod rotatable in the frame having a slotted end, a cutoff and gripper member rotatable in the frame on the axis of the rod, said member having a pair of diametrically opposite cam operated wire grippers and one element of a wire cutoff adjacent each gripper, a cam stationary on the frame for actuating said grippers when the member rotates, another element of said cutoff being fixed on the frame to cooperate with the said one elements thereof upon rotation of the member, and means gearing the rod and member together so that the rod makes a plurality of half-revolutions for one half-revolution of the member.

30 9. In a twister unit of the nature described; a frame, a twister rod rotatable in the frame having a slotted end, a cutoff and gripper member rotatable in the frame on the axis of the rod, said member having a pair of diametrically opposite cam operated wire grippers and one element of a wire cutoff adjacent each gripper, a cam stationary on the frame for actuating said grippers when the member rotates, another element of said cutoff being fixed on the frame to cooperate with the said one elements thereof upon rotation of the member, and means gearing the rod and member together so that the rod makes a plurality of half-revolutions for one half-revolution of the member, said cam being arranged so the one gripper next to pass the fixed cutoff element is open to receive wire while the other gripper is closed, and upon initiation of rotation of the member the said one gripper is closed by the cam and the other is released.

40 10. In a twister unit of the nature described; a frame, a twister rod rotatable in the frame having a slotted end, a cutoff and gripper member rotatable in the frame on the axis of the rod, said member having a pair of diametrically opposite cam operated wire grippers and one element of a wire cutoff adjacent each gripper, a cam stationary on the frame for actuating said grippers when the member rotates, another element of said cutoff being fixed on the frame to cooperate with the said one elements thereof upon rotation of the member, and means gearing the rod and member together so that the rod makes a plurality of half-revolutions for one half-revolution of the member, said cam being arranged so the one gripper next to pass the fixed cutoff element is open to receive wire while the other gripper is closed, and upon initiation of rotation of the member the said one gripper is closed by the cam and the other is released, said grippers remaining in their last mentioned positions during the remainder of the half-revolution of said member.

50 11. In a twister unit; a frame, a twister rod rotatable in the frame having a slotted end, a sleeve reciprocable and rotatable on the rod having a projecting part with a lateral notch positioned to engage the ends of wires twisted by rotation of said rod, a helical gear portion on the sleeve and a helical drive gear meshing therewith, a guide member projecting from the gear portion, means defining a slot comprising a portion axial of said sleeve and a portion

11

circumferential of said sleeve receiving said member whereby rotation of said drive gear first reciprocates the sleeve and then rotates the sleeve, means for rotating said rod, and means operable after a predetermined angular movement of the rod to rotate said drive gear.
